SUPPORTING MEMBER

Frederick A. Niemann, Chicago, Ill., assignor to
 Felt & Tarrant Mfg. Co., Chicago, Ill., a corpora-
 tion of Illinois

Application May 13, 1936, Serial No. 79,504

3 Claims. (Cl. 248—188)

This invention relates in general to supporting members, and more particularly to a folding leg member for drawing boards, distribution boards, and the like.

5 A principal object of the invention is the provision of a supporting member having one portion adapted to be rigidly secured to the object to be supported and another part mounted thereon so as to be readily movable to operative or inoperative position and be automatically retained in either of such positions.

10 Another important object of the invention is the provision of a folding leg member having a novel type of joint which enables movement 15 of the leg from folded to extended position in one motion accompanied by an automatic locking of the leg in such extended position.

Numerous other objects and advantages of the invention will be apparent as it is better 20 understood from the following description, which, when taken in connection with the accompanying drawing, discloses a preferred embodiment thereof.

In the drawing,
 25 Figure 1 is an elevational view of a supporting member embodying the features of the invention, with the leg portion in extended position;

Fig. 2 is a vertical sectional view taken substantially on the line 2—2 of Figure 1;

Fig. 3 is an elevational view, partly in section, with the leg portion of the supporting member in folded or inoperative position; and

Fig. 4 is a top plan view of the device of Fig. 2.
 30 Referring more particularly to the drawing, the supporting or folding leg member illustrated comprises a disk 11 adapted to be rigidly secured in the usual manner to the drawing board, distribution board, or the like (not shown) which is to be supported, as by means of screws extending through apertures 12 in the disk. The disk 11 is also provided with a depressed portion 13 and an aperture 14 located centrally thereof (Fig. 2).

Extending downwardly through the aperture 14 is a stud 15 having a circumferential flange 16 at its upper end bearing against the upper surface of the depressed portion 13 of the disk 11. The stud 15 is rigidly secured to the disk 11 in any suitable manner, such as by welding. The main portion of the stud 15 is cylindrical in shape and is provided with a longitudinal slot 17 extending upwardly from its lower surface to a point adjacent the flange 16. The stud 15 is 50 also provided with a horizontal bore 18 disposed

at right angles to the slot 17 and having a reduced portion 19 extending outwardly a short distance from one of the side surfaces of the slot 17 for a purpose to be later described.

A link 21 is positioned with its upper end 5 within the slot 17 of the stud 15, and is pivotally mounted on a pin 22 which is disposed within the bore 18. One end of the pin 22 is reduced to fit the smaller portion 19 of the bore 18 and to provide a shoulder which abuts against the side surface of the slot 17. The outer end of this reduced portion of the pin 22 may then be riveted 10 against the shoulder formed at the outer end of the reduced portion 19 of the bore 18 to secure the pin 22 to the stud 15. In this manner the 15 pin 22 does not extend beyond the outer surface of the stud 15.

The link 21 is provided with a longitudinal slot 23, and the outer edges of the link are rounded so as to fall substantially within the 20 curved plane of the outer surface of the cylindrical portion of the stud 15 when the link 22 is in its vertical position of Fig. 2.

A tubular member 24, comprising the supporting leg proper, is adapted to fit slidably over the 25 main cylindrical portion of the stud 15, as shown in Fig. 2. A stop pin 25 extends through the slot 23 in the link 21 and is rigidly mounted in the walls of the tubular member 24. Adjacent its other end, the tubular member 24 is provided 30 with a cross-pin 26 to which is anchored one end of a coil spring 27, the other end of which engages the slotted end of the link 21. The tubular member 24 is thus resiliently secured to the disk 11 and is movable thereto within definite 35 limits.

The lower end of the bore of the tubular member 24 is threaded at 28 (Fig. 2) to receive a reduced threaded end portion 29 of a rod 31, comprising an extension of the tubular member 24. The other end of the rod 31 is bored and tapped at 32, and is adapted to receive an insert or plug 33 made of rubber, or the like, to prevent slipping of the support or injury to the surface upon which it rests. It will be readily apparent 40 that the plug 33 may be inserted in the threaded bore 28 of the tubular member 24 and the rod 31 omitted, or other extension members similar to the rod 31 added, to provide a supporting leg of any desired length.

The exterior surfaces of the tube 24 and rod 31 are knurled for a portion of their length, as indicated at 34 and 35, respectively, to facilitate movement thereof relative to each other and to the disk 11.

55

In use, the instant supporting member is in its extended or vertical position of Figs. 1 and 2 with the upper end of the tube or leg 24 surrounding the stud 15. In this operative position, the 5 end of the tube 24 is urged into firm contact with the depressed portion 13 of the disk 11, to provide a very rigid supporting structure.

When it is desired to move the tube or leg 24 to inoperative or folded position, as shown in Fig. 10 3, it is merely pulled downwardly away from the disk 11 against the tension of spring 27 until its upper end is slightly below the lower end of the stud 15. The tube 24 and link 21 may then be 15 swung about the pivot pin 22 into a substantially horizontal position, that is, into an inoperative or folded position in which the longitudinal axes of the members 24 and 21 are parallel to the plane of the disk 11 (Fig. 3). The several parts are resiliently maintained in this position by 20 means of the spring 27 urging the tube 24 into firm contact with the side surface of the stud 15.

In moving the tube or leg 24 back to extended or operative position, it is pulled longitudinally away from the stud 15, and swung with the link 25 21 about the pivot pin 22 into a perpendicular position relative to the disk 11, where it will be automatically locked in place by the action of the spring 27. Or, such movement of the leg 24 from folded to operative position may be accomplished 30 by a uni-directional impulse, since pivotal movement only of the members 24 and 21 from their position of Fig. 3 will result in the end of the tube 24 being cammed on the outer surface of the stud 15 until it reaches a position in which it can 35 slide over and surround the stud. This uni-directional impulse may be applied directly to the leg 24 or indirectly by a snapping or shaking movement of the object to be supported to which the disk 11 is secured.

40 In any of the longitudinal movements of the tube or leg 24 away from the stud 15 and against the tension of the spring 27, the pin 25, in conjunction with the slot 23 in the link 21, will prevent complete separation or disconnection of the several parts of the supporting structure from 45 each other.

It is thought that the invention and many of its attendant advantages will be understood from the foregoing description, and it will be apparent that various changes may be made in the form, 50 construction and arrangement of the parts without departing from the spirit and scope of the

invention or sacrificing all of its material advantages, the form hereinbefore described being merely a preferred embodiment thereof.

I claim:

1. In a folding support, an attaching plate 5 adapted to be secured to an object to be supported, a downwardly extending stud mounted on said plate, a link pivotally mounted on said stud having an elongated slot therein, a tubular leg member resiliently secured to said link, and a pin 10 mounted in said leg and extending through said slot for limiting the relative movement between said leg and said link.

2. In a folding support, an attaching plate adapted to be secured to an object to be supported, a downwardly extending stud mounted on said plate, a link pivotally mounted on said stud having an elongated slot therein, a tubular leg member, an extension spring housed within said leg member and secured at one end thereto 20 and at the other end to said link, and a pin mounted in said leg and extending through said slot to limit movement of said leg against the action of said spring between operative and inoperative positions, said leg abutting against said 25 stud to limit movement thereof by said spring in inoperative position and embracing said stud and abutting against said plate to limit movement thereof by said spring in operative position.

3. In a folding support, an attaching plate, 30 comprising a flat portion adapted to be secured to an object to be supported, and an embossed portion spaced downwardly from the plane of said flat portion and having an aperture therein, a stud having a flange disposed within the embossed portion of said plate below the plane of said flat portion and secured thereto and a body portion extending downwardly through said aperture, a link pivotally secured to the body portion of said stud and having an elongated slot therein, 35 a tubular leg member, a spring disposed within said leg and connected at one end thereto and at the other end to said link, and a pin mounted in said leg and extending through said slot to limit outward movement of said leg relative to 40 said link, whereby said leg may be moved relative to said plate between operative and inoperative positions and is adapted in operative position to abut against said plate and completely conceal said stud and said link. 45
